VARIABLE RESISTOR

Richard E. Caddeck, Ames, Iowa, and Warren D. Hubert, Riverside, Calif., assignors to Bourns, Inc., a corporation of California

Filed Apr. 29, 1959, Ser. No. 809,771

5 Claims. (Cl. 338—180)

The present invention relates to variable resistors, and more particularly to precision potentiometers of the type wherein a wiper is moved along a resistance element by means of a rotatable leadscrew. One of the primary objects of the invention is to provide a potentiometer of the class described, which is sealed against the entrance of humidity and dust, and which is so constructed as to permit its manufacture in extremely small sizes.

A further object of the invention is to provide a leadscrew actuated potentiometer having a high degree of reliability, exceptional stability of settings, and extreme accuracy of adjustment.

Another object is to provide a leadscrew actuated potentiometer which is extremely simple in construction, and which can be quickly and easily assembled.

Still another object of the invention is to provide a leadscrew actuated potentiometer capable of operating at relatively high temperature.

These objects are achieved in the present invention by a construction embodying a housing or body of high temperature resistant plastic having a cavity formed in one side thereof, in which a leadscrew is journaled. Mounted on the said one side of the housing is a lid holding a resistance element having a ceramic mandrel. A slider is operatively associated with the leadscrew and has a contact wiping on the element, the said slider forming an electrical connection between the element and the leadscrew. Terminals are electrically connected to the leadscrew and to the resistance element, and a screw adjusting head is connected to one end of the leadscrew by a non-conductive coupling member.

The construction of the slider forms one aspect of the invention and comprises a U-shaped sheet metal body which engages the leadscrew from below and fits snugly against opposite sides thereof. A generally U-shaped spring wire contact member has its ends anchored in the bottom of the slider body adjacent one end thereof, and the arms of the spring wire contact member are bowed into an arc of approximately 180 degrees and extend upward alongside the leadscrew adjacent the other end of the slider body. The center portion of the U-shaped contact member passes through vertical guide slots in the sides of the slider body, and extends across the top of the leadscrew, yieldingly engaging the thread of the leadscrew midway between the ends of the slider body to provide a releasable driving connection between the slider and the leadscrew. Electrical connection is made between the resistance element and the leadscrew by the contact member, and the leadscrew is electrically connected, in turn, to one of the terminals by means of a spring clip of novel construction, having an aperture through which one end of the leadscrew passes, and a bowed spring finger which overlies the leadscrew and presses against the same with spring pressure.

The foregoing and other objects and advantages of the invention will become apparent to those skilled in the art upon consideration of the following detailed description of a preferred embodiment thereof, reference being had to the accompanying drawings, wherein:

FIGURE 1 is a longitudinal section, taken at 1—1 in FIGURE 2, through a leadscrew actuated potentiometer embodying the principles of the invention;

FIGURE 2 is a transverse sectional view of the same taken at 2—2 of FIGURE 1;

2

FIGURE 3 is a sectional view, taken at 3—3 in FIGURE 1; and

FIGURE 4 is an exploded perspective view of the housing and lid of the instrument illustrated herein.

5 In the drawings, the instrument is designated in its entirety by the reference numeral 10, and is seen to comprise a generally rectangular body 11 of electrically non-conductive, high temperature plastic or equivalent material, having a cavity 12 formed in one side thereof, 10 and a lid 13 mounted on said one side to enclose said cavity. The main portion of the cavity 12 is relatively deep, and occupies approximately two-thirds of the length of the housing in the mid-portion thereof; there being a relatively shallow portion 14 of the cavity extending 15 from one end of the main portion 12 to the adjacent end of the body 11. The sides of the cavity are flat and substantially parallel, except for narrow shoulders 15 and 16, which extend lengthwise of the body along the sides thereof. At the end of the body opposite the shallow portion 14, the cavity is provided with a step 20, which provides support for one end of the lid 13.

Rotatably supported within the body 11 parallel to the longitudinal axis thereof, is a leadscrew 21 having a smooth unthreaded portion 22 at one end thereof. The smooth portion 22 of the leadscrew is inserted into and journaled within a smooth bearing hole 23. At its other end, the leadscrew 21 is enlarged in diameter to provide a smooth surfaced cylindrical portion 24, which is journaled within a bore 25 in the body 11. The enlarged cylindrical portion 24 of the leadscrew is provided with a circumferential groove 26, which is engaged by a U-shaped retainer 30 that is seated within the housing 11, to hold the leadscrew against endwise movement.

The enlarged portion 24 of the leadscrew terminates 35 within the bore 25, and is provided with a socket 31 in its end, into which is inserted one end of a coupling member 32 of ceramic or other electrically non-conductive material. The other end of the coupling member 32 is inserted into a socket 33 in a head 34, which is disposed 40 within a slightly enlarged counterbore 35 in the end of the body. The outer end of the head 34 projects beyond the end of the body 11 and is slotted at 36 to receive a screwdriver blade. The coupling member 32 is an interference fit in both of the sockets 31 and 33, and thus the head 34 is fixedly connected to the leadscrew 21 so that the two rotate as one. The adjacent ends of the enlarged portion 24 and head 34 are spaced apart slightly to form a circumferential groove, and disposed within this groove is an O-ring 40 of elastomeric material, which 45 seals the clearance between the leadscrew and the body 11 against the entrance of moisture or dirt into the cavity.

The lid 13 is likewise formed of non-conductive material, and is provided with an outer surface 41, which 50 is flush with the outer surface of the body 11 when assembled in place. One end of the lid 13 is provided with a ledge 42 which seats on the step 20, while the other end 43 is relatively shallow to fit within the shallow groove 14, and is provided with a shallow channel 44 on its inner surface (see FIGURE 4) to form an aperture through which the terminal wires pass. Between the ledge 42 and end portion 43, the lid 13 has sides 46 and 47, which project down into the cavity 12 and seat on the shoulders 15. The sides 46 and 47 are connected at one end by an end wall 48, which fits against the end of the cavity 12 and abuts against the leadscrew retainer 30 to hold the latter in place.

The inwardly projecting portion of the lid 13 has a narrow slot 50 provided therein, with slightly enlarged end portions 51 and 52. Seated within the slot 50, 51, 52 is a resistance element 53, which may either be of the wire-wound type, as shown, or it may be a composition ele-

ment. In the illustrated embodiment, wire windings are wrapped around a ceramic mandrel 54 which is apertured centrally at 55 to receive a terminal strip 56. The terminal strip 56 extends through the mandrel from one end thereof to the other, and at its right-hand end (FIGURE 1) the strip is bent around at 57 to overlie the windings at the end of the element, where it is silver soldered or otherwise electrically connected to the resistance wire or composition. The left-hand end of the strip 56 projects beyond the end of the mandrel 54, and is soldered or spot welded to a terminal wire 69 lying within the channel 44 in the lid 13. The resistance wire windings at the left-hand end of the element are electrically connected by a tab 61 to the upturned end of a terminal wire 62, which is likewise disposed within the channel 44 of the lid 13. The terminal wires 60 and 62 are separated from one another by a triangularly shaped spacer 63 which projects upwardly from the bottom of the channel 44. Also, terminal wire 62 extends upwardly through a diagonal slot 64 in the end of the body 11, so that the terminal wires are spaced apart where they leave the instrument body.

When the lid 13 is assembled to the body 11, the resistance element 53 extends parallel to the leadscrew 21 and is spaced a short distance therefrom. Associated with the leadscrew 21 and operatively connected therewith is a slider 65 having a contact member 66 which wipes on the top surface of the resistance element 53 to form an electrical connection between the element and the leadscrew. The slider 65 is preferably formed of sheet metal bent into a generally U-shaped configuration, and engages the leadscrew 21 from below. The slider 65 has a bottom 70 and upwardly projecting sides 71 at opposite sides thereof. The contact 66 includes a portion lying on top of the bottom 70, and is bent down over one end and back at an angle to provide a spring finger having a rounded end portion 72 that wipes on the resistance element. The portion of the contact member 66 overlying the bottom 70 is silver soldered or spot welded to the said bottom portion, and bears against the underneath side of the leadscrew, to make electrical contact therewith. The sides 71 of the slider fit snugly against opposite sides of the leadscrew 21, as shown in FIGURE 2, and formed in the top edges of the sides are vertical guide slots 73, the purpose of which will be explained presently.

The driving connection between the leadscrew 21 and slider 65 is effected by means of a spring wire member 74 which is bent into a generally U-shaped configuration, with its ends projecting up into holes in the bottom 70 of the slider, where they are soldered or otherwise rigidly joined to the bottom 70. As best shown in FIGURE 1, the sides of the spring wire member extend downwardly and to the right from their point of attachment, and then extend upwardly and rearwardly in an arcuate bow along both sides of the leadscrew to the point where they join the center section 74' that extends transversely across the top of the leadscrew. This transverse center portion 74' of the spring wire extends through and is slidable vertically within the guide slots 73, so that its movement is restricted by the slots. The center portion 74' of the spring wire member yieldingly engages the thread of the leadscrew, so that as the leadscrew is turned, the slider 65 is moved lengthwise thereof.

Being free to move vertically within the guide slots 73, the center portion 74' of the spring wire member 74 is adapted to ride up over the crests of the leadscrew threads when the leadscrew is forcibly turned while the slider is restrained against free movement lengthwise of the leadscrew, as when the slider has reached either end of its travel. The long length of spring arm afforded by the bowed side portions of the spring member 74 provides a considerable amount of resiliency, allowing the center portion 74' to ratchet over a turn of the leadscrew thread without unduly stressing the sides of the spring wire member. It will also be noted that the spring wire member 74' engages the leadscrew thread approximately half way be-

tween the ends of the slider 65. This is an important feature, as it tends to stabilize the slider by holding both ends of the bottom 70 firmly against the bottom of the leadscrew. The slider is thus prevented from becoming cocked at an angle to the leadscrew, as might otherwise happen if the spring wire member engaged the leadscrew adjacent one end of the slider. Tabs 80 are bent downwardly from opposite sides of the bottom 70 of the slider adjacent one end thereof, and these tabs 80 slidably engage the sides of the body 11, as shown in FIGURE 2, so as to restrain the slider against turning with the leadscrew.

Those skilled in the art will recognize from the foregoing description that the leadscrew 21 serves as an electrical return from the contact 66. The leadscrew is adapted to be connected into the electrical circuit with which the potentiometer 10 is to be used, by means of a terminal wire 81 which extends through a hole 82 in the end of the body 11. The terminal wire 81 projects into the cavity 12 and through an aperture 83 in a leadscrew terminal clip 84, which bears against one end of the cavity 12. The terminal clip 84 is also provided with a circular aperture 85 through which the smooth bearing portion 22 of the leadscrew 21 passes. Flanges 86 are bent inwardly from the side edges of the clip 84, and these flanges bear against the sides of the cavity 12 to hold the clip against lateral displacement. Bent downwardly from the top edge of the clip 84 is a bowed spring finger 87, the free end of which yieldingly presses against the smooth bearing portion 22 of the leadscrew to make electrical contact therewith. The terminal wire 81 lies against one of the side flanges 86 and is silver soldered or otherwise suitably joined thereto.

The potentiometer 10 is adapted to be mounted upon a suitable supporting structure, and to this end the body 11 is provided with a pair of mounting holes 90 adjacent the ends of the body. Mounting screws may be passed through the holes 90 to secure the body 11 to the supporting structure.

In assembling the potentiometer 10, the leadscrew 21 with the head 34 and coupling member 32 assembled thereto is inserted through the bore 25, and the slider 65 is slipped over the inner end of the leadscrew so that the spring wire member 74 is operatively engaged with the threads of the leadscrew. The smooth bearing portion 22 of the leadscrew is then inserted through the hole 85 in the terminal clip 84, and into the bearing hole 23. When the leadscrew 21 is fully seated in the body 11, the retainer 39 is slipped down into the cavity 12 so that it engages the circumferential groove 26 in the large bearing portion 24 at the head end of the leadscrew. The resistance element 53, with terminal wires 60 and 62 attached thereto, is then inserted into the cavity 50, 51, 52 in the lid 13, and the lid is dropped into place in the open side of the body 11, so that it closes the cavity 12. The lid 13 is cemented to the body around its entire edge, and the apertures in the end of the body through which the terminal wires 60, 62 and 81 pass are then filled with a suitable potting agent, such as epoxy resin 95. The instrument is then ready for use.

While we have shown in considerable detail what we believe to be the preferred form of our invention, it will be understood by those skilled in the art that various changes may be made in the shape and arrangement of the several parts without departing from the scope of the following claims.

We claim:

1. A variable resistor comprising an elongated body having a cavity formed in one side thereof, a lid mounted on said one side of said body of enclose said cavity, a resistance element mounted on the inner face of said lid and having a pair of terminal wires connected to the ends thereof, said lid having one end portion projecting to the end of said body, said projecting one end portion being received within a shallow groove in said one side of said body and cooperating therewith to form an

aperture through which said terminal wires pass, a lead-screw rotatably supported on said body within said cavity parallel to said resistance element, a slider operatively engaged by said lead-screw to be moved thereby, said slider having a contact wiping on said resistance element and electrically connected to said lead-screw, and a third terminal wire electrically connected to said lead-screw.

2. A variable resistor comprising a body, a resistance element mounted on said body, a lead-screw of conductive material disposed parallel to said resistance element and rotatably supported at its ends by said body, said lead-screw having a smooth unthreaded portion adjacent one end thereof, a slider operatively engaged by said lead-screw so as to be moved thereby when the lead-screw is turned, contact means on said slider wiping on said resistance element and making electrical connection with said lead-screw, a lead-screw terminal clip of conductive sheet metal comprising a first part perpendicular to the axis of said lead-screw and a second part perpendicular to said first part, said first part having an aperture provided therein through which said smooth portion of said lead-screw extends, said second part having a lip at its outer end yieldingly engaging said smooth portion of said lead-screw to make electrical contact therewith, and terminal means connected to said clip.

3. A variable resistor comprising an elongated body having a cavity formed in one side thereof, an electrically conductive lead-screw extending through said cavity and journaled at its ends in the ends of said body, said lead-screw having a smooth unthreaded portion adjacent one end thereof, a lid mounted on said one side of said body to enclose said cavity, a resistance element mounted on the inner face of said lid parallel to said lead-screw, a slider operatively engaged by said lead-screw so as to be moved thereby when the lead-screw is turned, contact means on said slider wiping on said resistance element and making electrical connection with said lead-screw, a lead-screw terminal clip of conductive sheet metal, said clip having a center portion disposed perpendicular to the longitudinal axis of said lead-screw, and side portions bent at right angles to said center portion so as to lie flat against the side walls of said cavity, said center portion having an aperture provided therein through which said smooth portion of said lead-screw passes, a top portion bent at right angles to said center portion so as to overlie said lead-screw, said top portion having a lip yieldingly

engaging said smooth portion of said lead-screw to make electrical contact therewith, and terminal means connected to said clip.

4. In a variable resistor having a housing, a lead-screw rotatably supported on said housing, and a resistance element mounted on said housing parallel to said lead-screw, the improvement comprising a slider consisting of a generally U-shaped sheet metal body, the bottom of said U-shaped slider body bearing against the bottom of said lead-screw and the sides thereof extending upwardly along opposite sides of the lead-screw, said sides having generally vertical guide slots formed in the top edges thereof adjacent the midpoint of said body, a spring wire member bent into a generally U-shaped configuration, the ends of said spring wire member being anchored in the bottom of said slider body adjacent one end thereof, the arms of said spring wire member being bowed and extending upwardly alongside said lead-screw adjacent the other end of said slider body, the center portion of said spring wire member extending transversely across the top of said lead-screw and yieldingly engaging the thread thereof, said center portion of said spring member being slidably vertically within said guide slots to allow the same to ride up over the crests of the lead-screw thread when said lead-screw is forcibly turned while said slider is restrained against free movement lengthwise of the lead-screw, and a contact member attached to the bottom of said slider body and wiping on said resistance element.

5. The invention as defined in claim 4, wherein said slider body has tabs bent downwardly from the bottom thereof adjacent the sides, said tabs slidably engaging the sides of said housing so as to prevent said slider body from turning with said lead-screw.
